SYRINGE

Edith Holtman, New York, N. Y., assignor to
Durex Products, Incorporated, New York, N. Y.,
a corporation of New York

Application July 15, 1939, Serial No. 284,627

12 Claims. (Cl. 128—260)

This invention relates to syringes for applying medicaments in the form of liquid, powder or jelly to the interior of the body and more especially to a type of syringe in which a definite known amount or quantity of the medicament may be automatically expelled into the body.

An object of the invention is to provide a syringe in which the amount of medicament taken in, while of known value, may be readily varied to the end of injecting into the body a medicament of any desired quantity within the limits of the capacity of the syringe.

A further object is to provide a syringe in which the amount of medicament drawn into or expelled from it may be readily varied without disturbing the relationship of the operating bulb with reference to the tube or barrel of the syringe.

Another object of the invention is to provide a syringe of the type having a movable plunger with a rod or operating member adapted to frictionally engage the plunger so that the liquid, jelly or powder contained in the syringe may be ejected forcibly and thus thoroughly distributed over the bodily surfaces to be medicated. In further pursuance of this object means are provided whereby a frictional driving connection between the operating rod and the movable plunger may readily be established.

Other objects and advantages will appear as the description of the particular physical embodiments selected to illustrate the invention progresses. For a better understanding of the invention, however, reference is made to the accompanying drawing in which like reference characters designate like parts throughout the several views, and in which:

Fig. 1 is a longitudinal sectional view of a syringe embodying the invention;

Fig. 2 is a view of a syringe showing a modified form of the invention, the lower portion being shown in section and the upper portion in front elevation and;

Fig. 3 is a fragmentary sectional view showing a modified form of connection between the adjusting rod and valve of the syringe.

Referring first to Fig. 1 the syringe is shown as comprising a substantially cylindrical tube 1 within the bore 2 of which is adapted for snug sliding engagement a solid freely floating piston 3 made of any suitable rigid material. The lower end of tube 1 is provided with a constricted portion 4 for the purpose of engaging the piston 3 and preventing it from being ejected from the tube. If desired, the constricted portion 4 may

be interiorly threaded, as at 5, for a purpose to be described later. The upper end of tube 1 is shown as provided with an enlarged collar 6 to provide a shoulder 7, a flexible hollow bulb 8, preferably formed of rubber, having its lower end 9 seated on the shoulder 7 and its exterior peripheral surface 10 compressed against the interior surface of collar 6 to provide an airtight connection between the tube 1 and bulb 8.

In order to provide an adjustable stop to limit the upward motion of piston 3, the upper end of bulb 8 is provided with a cylindrical aperture 11 in alignment with the axis of tube 1. A rod 12 of slightly greater diameter than aperture 11 passes through the bulb 8 and has its lower end 15 disposed for engagement by the piston 3, a suitable knob or handle 13 being provided on the upper end of rod 12. Means may be provided for centering the lower end of rod 12 within tube 1, that shown comprising a transversely extending disc 14 secured to rod 12 and slidable within the bore 2, the disc 14 being provided with one or more apertures 15 to permit the passage of air against the piston 3 from the bulb 8. Means is provided to secure a frictional engagement between the rod 12 and piston 3 for a purpose to be later described. In the form of invention shown in Fig. 1, the lower end of rod 12 has a longitudinal slot 16 to provide a tip which gives slightly when it enters a central cylindrical recess 17 provided in the upper side of piston 3 to receive it. It is preferable to provide a small opening through the bulb 8 for the purpose of slowly venting air during the operation of the syringe, such an opening being indicated at 18. The tube 1 may be made of any suitable material but is preferably made of a transparent material such as glass, molded plastic material etc. so that its contents may readily be observed.

The embodiment of the invention shown in Fig. 2 is generally similar to that shown in Fig. 1 but in this form the lower end 9a of the bulb 8a fits around the upper end of tube 1a which is the same diameter as the main body of the tube. Also in this form, the lower constricted end 4a of the tube is not provided with any screw thread but such a thread may be provided if desired. In order to provide a frictional connection to the piston 3a, its upper surface is provided with a cylindrical projection 19 adapted for frictional engagement with the interior wall 20 of a short piece of rubber tubing 21 which is firmly secured to the lower end of the stop rod 12a by any suitable means, not shown.

In the form of connection shown in Fig. 3, the

tip of the stop rod 12b is tapered so as to present a conical surface 22 which is adapted to enter a similar shaped aperture 23 formed in the piston 3b. It will also be understood that instead of being conical shaped, the tip of rod 12b may have the shape of a parabola or any other curved surface which will provide a good frictional contact with the piston 3b.

In the operation of the syringe, the lower end 10 of tube 1 is inserted into a vessel containing the medicament which it is desired to apply and which may be in the form of either a liquid, jelly or powder. The bulb 8 is then compressed which causes the piston 3 to move to the end of tube 1, 15 as shown by dash lines in Fig. 1. Upon releasing the bulb 8 a partial vacuum is created above the piston 3, the pressure differential between its lower and upper surfaces causing it to move upwardly within the tube until it engages the tip of rod 12. A volume of the medicament corresponding to that of the portion of tube 1 traversed by the piston, is drawn into the tube and is ready for application to the interior of the body by the insertion of the end of the tube into the body cavity. 20 The volume drawn into the tube may be readily adjusted to a definite, desired amount by adjusting the end of rod 12 to the proper position within the tube. The handle 13 facilitates this adjustment, as it may be readily grasped to slide 25 the rod in either direction within the aperture 11 in the bulb 8. By providing a frictional connection between the end of the stop rod and piston 3, the piston remains seated on the rod while the bulb 8 is being compressed until a sufficient air pressure is built up in the tube above the piston 30 to cause it to be suddenly and forcibly pushed off the tip of the rod 12 or end of the tube 21 of Fig. 2. This sudden downward displacement of the piston expels the medicament from the end 40 of the tube with force causing it to reach and be well distributed over the surface requiring medication.

In case the medicament is supplied in a collapsible tube having a screw threaded top, such 45 top is screwed into the thread provided at the lower end of tube 1, such as the thread 5, whereupon pressing the walls of the collapsible tube causes the medicament, such as a jelly, to enter tube 1 and displace valve 3 upwardly until it 50 engages and is arrested by the stop rod. This automatically measures out the desired amount of medicament, the rod 12 having previously been set in the proper position to provide the desired dosage. To apply the medicament, the bulb 8 55 is compressed and the operation of the syringe is the same as above described.

I have described what I believe to be the best embodiments of my invention. I do not wish, however, to be confined to the embodiments 60 shown, but what I desire to cover by Letters Patent is set forth in the appended claims.

I claim:

1. A syringe comprising a tube, a piston movable along the inner surface of the tube, means 65 at one end of the tube for confining the piston against displacement from the tube, a flexible bulb connected to the other end of the tube, a stop within the tube adapted to engage the piston as the piston moves toward the flexible bulb and an adjusting element having means external to both the tube and flexible bulb for adjusting the

stop along the tube while the bulb and tube remain relatively fixed.

2. A syringe as set forth in claim 1 in which the adjusting means comprises a rod-like member extending longitudinally along the tube and passing through the flexible bulb. 5

3. A syringe as set forth in claim 1 in which the flexible bulb is provided with an aperture substantially in alignment with the tube and the adjusting means comprises a rod-like member 10 passing through said aperture and extending longitudinally along the tube, the diameter of the rod-like member being slightly greater than that of said aperture.

4. A syringe comprising a tube having a constricted lower end provided with a screw thread, a flexible bulb connected to the upper end of the tube, a piston movable along the inner surface of the tube, a stop within the tube and adapted to limit the upward movement of the piston along 20 the tube and an adjusting element having means external to both the tube and flexible bulb for adjusting the stop along the tube while the bulb and tube remain relatively fixed. 15

5. A syringe comprising a tube, a piston movable along the inner surface of the tube, means at the lower end of the tube for confining the piston against displacement from the tube, a flexible bulb connected to the upper end of the tube and a rod passing through the flexible bulb 30 and having its lower end disposed within the tube and adapted to engage the piston and limit its motion upwardly along the tube. 25

6. A syringe as set forth in claim 5 in which a transversely extending disc is provided within 35 the tube, said disc being provided with a central bore adapted to receive the rod.

7. A syringe as set forth in claim 5 in which the upper side of the piston is provided with a bore and the lower end of the rod is adapted to frictionally engage the marginal surface of the bore. 10

8. A syringe as set forth in claim 5 in which the upper side of the piston is provided with a cylindrical bore and the lower end of the rod is slotted longitudinally and adapted to frictionally engage the marginal surface of the bore. 45

9. A syringe as set forth in claim 5 in which the upper side of the piston is provided with a tapered bore and the lower end of the rod is correspondingly tapered to enter and frictionally engage the marginal surface of the bore. 50

10. A syringe as set forth in claim 5 in which the piston is provided with an upwardly extending pin and the lower end of the rod is provided with a short piece of flexible tubing adapted to frictionally engage the surface of said pin. 55

11. A syringe comprising a tube, a piston slideable within the tube, means at the lower end of the tube for confining the piston against displacement from the tube, a flexible bulb connected to the upper end of the tube and provided with an aperture in its upper end above the tube, and a rod-like member passing through said aperture and adapted for close frictional engagement with the flexible bulb, the lower end of said member being disposed for engagement by the piston. 60

12. A syringe as set forth in claim 11 in which the upper end of the rod is provided with an 65 operating handle. 70
